1

For rolling (ironing) or smoothing leather, more particularly shoe sole leather, bridge rolling machines are used provided with a heavy reciprocating roll for smoothing the leather. The rolling pressures implied in such a process are very high and with the present construction of the rolling machines, the pressures exerted have an adverse effect on the borders of the shoe sole leather being treated. The high pressure exerted by the pressure generating means on the working roll which after its passage over the leather under treatment falls from the border of the latter down onto the metal plate of the working table, crushes the borders of the leather when the roll slips down over the edge of the leather and then moves up again over such edge, since the borders cannot resist such a high instantaneous pressure. A leather which has been damaged in this way gives rise to a considerable increase of waste during its further treatment, i. e. cutting off and stamping of sole pieces therefrom.

To avoid such an undesirable damage to the leather use has been made e. g. of supporting pieces which the assistant places against the edges of the leather under treatment when the roll rides on and off the leather. However, this auxiliary provision not only complicates the work of the assistant, but also leads to a high risk of injury each time the assistant inserts the supporting pieces under the moving roll.

In order to eliminate the imperfections referred to, it has been proposed, for instance, to mount the working roll in such a way as to prevent it from falling down onto the working plate of the table when the roll has passed over the leather edge. However, this construction has failed in practice mainly for the reason that the roll when moving back is still rotating, due to its inertia, in the same direction as during its preceding movement so that when riding again onto the edge of the leather, the oppositely rotating roll has to be arrested and then caused to rotate again, but in the direction of its reverse movement. The practical effect of the arrangement has been that the working roll, when riding on to the leather, causes the same to be folded or turned down in front of the advancing roll, crushing at the same time the leather edge.

It has been proposed further on to impart to the working roll a positive rotary motion in unison with the rolling movement of the roll over the leather. This arrangement permits to avoid the necessity of placing supporting pieces against the leather edges but has several disadvantages. The driving means for rotating the working roller is very complicated and in combination with a rope transmission is unsuitable for the rolling

process. Owing to its continuous winding and unwinding, the rope is subjected to considerable stresses and soon becomes damaged. Since it is practically impossible to protect the rope by a cover throughout its length, broken wire pieces and particles of lubricant often fall down onto the leather which is being rolled and depreciate the same.

As a further solution an arrangement has been proposed in which the working roll, instead of being connected directly to the pressure generating means, is fastened to a rocking lever fixedly secured at its one side, the roll resting on the working table of the machine under the action of its own weight only, whereby the roll does not engage with the pressure exerting means until after the rocking lever has been caused to rock upwards, e. g. after the roll has been brought onto the leather to be smoothed. The disadvantages of this construction, such as e. g. the difficulties encountered in adjusting the pressure and the level of the pressure exerting means, have prevented this design from being extensively used in practice.

The present invention by providing a new and substantially improved mode of construction of the rolling device gives a very satisfactory solution to the fundamental problem, i. e. permits to avoid crushing of the borders of the leather under treatment by the working roll which rides on and off the leather under the effect of its proper weight only—without the influence of the pressure exerting means.

The essential feature of the present invention resides in completely separating the working roll from the pressure generating means in such a way as to make the roll bearable together with the roll freely slideable up and down along a path and within a space confined by the walls of the carriage frame and the thrust plates of the toggle levers of the pressure generating means.

With this construction the pressure exerting means may easily be adjusted by means of a single hand operated adjusting member for the desired rolling pressure, and by means of another hand operated member it is possible to adjust the pressure exerting means as a unit so as to raise or lower the same without affecting the adjusted rolling pressure. Thereby it is made possible to increase or decrease at will the clearances between the lower thrust plates of the pressure exerting means and the bearings of the working roll to suit the thickness of the leather under treatment.

When the working roll is being brought in contact with the leather, it is caused to bear on the leather under the effect of its own weight, while

2

the pressure exerting device which is adjusted to operate at the moment when the roller bearings have been raised to a distance equivalent to the thickness of the leather treated, is still inactive. It is not until the end phase of the movement of the working roll onto the leather has been reached, i. e. after the roll bearings have been brought in contact with the thrust plates of the toggle levers, that the previously adjusted pressure begins to act upon the bearings and thus upon the working roll and the leather to be smoothed. The reverse operation takes place when the roll slips down the leather under treatment. In this stage the rolling pressure of the pressure exerting device acts only during the period when the roll is travelling over the leather. As soon as the working roll begins to slip off the leather, the bearings of the roll move beyond the extreme point of the operating range of the pressure exerting device which thereby ceases to act upon the roll bearings and thus upon the roll itself, so that the latter slips down, under the effect of its own weight only, from the leather onto the plate of the working table.

By means of this apparatus, which is very simple in its principle and in design, perfectly sound borders are obtained on rolled raw leather without the aid of edge supporting pieces to be inserted beneath the moving roll.

An example of carrying out the invention will be described hereinafter with reference to the accompanying drawing in which:

Fig. 1 is a side view of the pressure generating device in combination with a separate working roll; and

Fig. 2 is a cross-section through the pressure generating device and the associated separate working roll on the line 2-2 of Fig. 1.

A carriage 3 movable to and fro is supported on an upper beam 1 by means of rollers 2. Reciprocating movement is imparted to the carriage 3 by means of a screw spindle 4. The pressure generating device comprises toggle levers 5, thrust plates 6 and sleeves 7 in which compression springs 8 are mounted. The springs 8 are adjusted to the required pressure by means of a regulating screw 9 and nuts 10. The regulating screw 9 is controlled from a hand wheel 11, Fig. 1, by means of a double chain transmission 21. The pressure generating device as a whole is hung by means of screws 12, Fig. 2, from the carriage 3. The screws 12 are interconnected by means of a chain 13, and by a hand wheel 14, Fig. 1, the pressure device may be raised or lowered as a unit through the intermediary of a double chain transmission 22 according to requirements. The working roll 15 with its bearings 16 rests always under its own weight on the working plate of the table 17, the said working plate being carried by a lower beam 18. Since the working roll 15 is formed separately from the pressure generating device, clearances 19 may be left between the lower thrust plates 6 and the bearings 16 of the roll, and the size of these clearances may be increased or decreased as required by turning the handwheel 14. The arrangement of the supporting rollers 20 is broadly known and is not comprised within the scope of the present invention. By forming the working roll 15 with its bearings 16 separately from the pressure exerting device and thus separately from the carriage 3, the carriage and the rollers 2 are substantially relieved.

What I claim is:

1. In a bridge rolling machine including a car-

- riage, a pressure exerting device mounted on the carriage comprising spring biased toggle levers and vertically movable thrust plates actuated by said toggle levers, and a vertically movable working roll having bearings engaged by said thrust plates, the arrangement of the bearings of the working roll so as to be completely separate from the pressure exerting device of the machine and to be freely movable up and down along a path and in a space confined by the walls of the carriage frame and by the thrust plates of the toggle levers of the pressure exerting device, the latter being mounted as an adjustable unit in the carriage frame in such a way that the clearances between the bearings of the working roll and the thrust plates of the toggle levers of the pressure exerting device are variable as required, within the limits of a free movement, not loaded by the said pressure exerting device, of the working roll.
2. In a bridge rolling machine including a carriage, a pressure exerting device mounted on the carriage comprising spring biased toggle levers and vertically movable thrust plates actuated by said toggle levers, and a vertically movable working roll having bearings engaged by said thrust plates, the arrangement of the bearings of the working roll so as to be completely separate from the pressure exerting device of the machine and to be freely movable up and down along a path and in a space confined by the walls of the carriage frame and by the thrust plates of the toggle levers of the pressure exerting device, the preliminary tension of the pressure exerting device being adjustable by independent adjusting means adapted to operate independently of the adjustment of the clearance between the bearings of the working roll and the thrust plates of the toggle levers of the pressure exerting device.
3. In a bridge rolling machine including a carriage, a pressure exerting device mounted on the carriage comprising spring biased toggle levers and vertically movable thrust plates actuated by said toggle levers, and a vertically movable working roll having bearings engaged by said thrust plates, the arrangement of the bearings of the working roll so as to be completely separate from the pressure exerting device of the machine and to be freely movable up and down along a path and in a space confined by the walls of the carriage frame and by the thrust plates of the toggle levers of the pressure exerting device, the latter being mounted as an adjustable unit in the carriage frame in such a way that the clearances between the bearings of the working roll and the thrust plates of the toggle levers of the pressure exerting device are variable as required, within the limits of a free movement, not loaded by the said pressure exerting device, of the working roll, the preliminary tension of the pressure exerting device being adjustable by means of an independent adjusting member adapted to operate independently of the adjustment of the said clearances.
